POWER TRANSMISSION

Warren P. Willett, Takoma Park, Md., assignor
to Vickers Incorporated, Detroit, Mich., a cor-
poration of Michigan

Application March 11, 1941, Serial No. 382,804

3 Claims. (Cl. 60—97)

This invention relates to power transmissions, particularly to those of the type comprising two or more fluid pressure energy translating devices, one of which may function as a pump and another as a fluid motor.

The invention is more particularly concerned with a power transmission system for operating a plurality of load devices exemplified by a hoist winch and wherein any one of the load devices may be operated at a time from a common pressure source selectively by a combination of valves and pump displacement controls.

In the operation of boat hoists aboard ship, it is frequently desirable to provide a common prime mover adjacent a group of boat hoists for selective operation of any one of the hoists. It is also desirable to provide means for positively driving the hoist in a paying out direction so that the hoist cable may be lowered to pick up a boat. It is also advantageous to arrange the drive so that one hoist may be operated to haul in its load at the same time that another hoist is being operated to pay out light cable. It is furthermore necessary that during the hauling-in operation the speed of hoisting be under absolute positive control as is also the case during paying out operation, whether the line be loaded or not.

It is an object of the present invention to provide an improved hydraulic power transmission system adapted to meet these requirements with a minimum of complication and which is inexpensive and reliable and positive in its operation.

Further objects and advantages of the present invention will be apparent from the following description, reference being had to the accompanying drawing wherein a preferred form of the present invention is clearly shown.

In the drawing the single figure is a diagrammatic view of a power transmission system incorporating a preferred form of the present invention.

In the form of the invention illustrated in the drawing, a prime mover, such as an electric motor 10, is positioned between two interconnected sump tanks 12 and 14 and is connected to drive at its opposite ends a fixed displacement pump 16 and a variable displacement pump 18.

From the pump 16 a delivery conduit 20, having the customary pressure responsive relief valve 22 connected therewith, extends to an inlet port 24 of a double-six-way, directional control valve 26. From the port 24 a continuation of the conduit 20 extends to the port 24' of a similar valve 26'. The valves 26 and 26' are duplicates and are connected with the pump and the tank in parallel, it

being understood that in the drawing and in the following description primed reference characters refer to corresponding parts associated with the valve 26'.

From the pump 18 a delivery conduit 28 connects with a second inlet port 30 of the valve 26 and the corresponding port 30'. The end return ports 32 and 34, which are connected together through a passage in the valve body, are connected by means of a return conduit 36 with the tank 12. The ports 38 and 40 which lie between the inlet ports and the return ports are connected by conduits 42 and 44 with the opposite sides of a rotary fluid motor 46. The latter is adapted to drive a winch drum 48 for hoisting and lowering a load such as a boat.

The valve 26 is provided with a spool 50 having three lands 52, 54 and 56 which are arranged to control communication between the various ports 20 in the well-understood manner. At the land 56 throttling grooves 58 are provided for producing gradual opening and closing of communication between ports 40 and 34. The spool 50 is biased to the left by a spring 60 and has a stem 62 at its 25 opposite end carrying a cam-following roller 64.

For the purpose of operating the valve an operating handle 66 is pivoted at 68 and carries a cam 70 coacting with the roller 64. Thus, when the handle is moved upwardly to the dotted line position marked "Hoist," the spool 50 will be shifted completely to the right, and, when the handle has been moved downwardly to the dotted line position marked "Lower," the spool 50 will be shifted completely to the left by the spring 60.

A second cam 72 is also mounted to move with the handle 66 and is so shaped that, when the handle 66 is moved from full line position to the hoisting position, a lever 74 is operated counterclockwise. When the handle 66 is moved downwardly to the lower position, the lever 74 remains stationary. The lever 74 is rigidly connected to a shaft 76 carrying at its lower end a lever 78. The latter is connected by a link 80 with a sliding stop or control rod 82 which abuts against a roller 84 carried by the swinging yoke 86 of the pump 18. The latter determines the displacement of the pump 18, and, when it is in the position shown, that is, in axial alignment with the shaft of motor 10, the pump displacement is zero. As the yoke 86 is moved clockwise, the pump displacement is increased in proportion to the angle through which it is moved. The control stem 82 is biased downwardly by a spring 88.

The swinging yoke 86 is also under the control of a pressure responsive regulator 90 which com-

prises a cylinder 92 in which a differential piston 94 is slidably mounted and biased upwardly by a spring 96. The latter is weaker than the spring 88 so that the spring 88 may always predominate over the spring 96. The stem 98 of piston 94 is connected by a link 100 to the yoke 86. The cylinder 92 is connected by a conduit 102 with the delivery conduit 28.

In operation, with the motor 10 running to drive the pumps 16 and 18 and with the parts in the position shown in the drawing, no fluid is delivered into conduit 28 by pump 18. The yoke 86 lies in neutral position. Since the discharge conduit 20 is blocked at the ports 24 and 24', the full delivery thereof is bypassed through the relief valve 22. This may be set at a relatively low pressure just sufficient to drive the motor 46 in a paying out direction.

When it is desired to haul in a load, the handle 66 may be operated in a clockwise direction, shifting valve spool 50 to the right and, at the same time, shifting the control stop 82 upwardly. The yoke 86 is accordingly swung upwardly in proportion to the amount of movement at handle 66 so that fluid is delivered into conduit 28 through ports 30 and 40 and conduit 44 to the motor 46. The latter is accordingly rotated at a speed depending upon the rate of fluid flow from the pump 18. Fluid exhausting from the motor 46 returns through conduit 42, ports 38 and 32, and conduit 36 to tank.

It will be seen that the hoisting speed is under complete control by the handle 66 and may be reduced or increased at will within the designed capacity of pump 18.

If, while the motor 46 is hauling in a load, it should be desired to pay out light cable at the motor 46', the handle 66' may be moved counter-clockwise, shifting spool 50' to the left. This opens a passage for fluid from pump 16 through conduit 20 to port 24', and from there through port 38', conduit 42', to motor 46'. The latter accordingly rotates in the paying out direction and returns exhausted fluid through conduit 44', ports 40' and 34' and conduit 36 to tank. The speed of rotation in the paying out direction is also under control at will by reason of the throttling grooves 58' which can be adjusted to restrict the exhausting fluid to any degree desired, thus causing pressure to build up in the conduit 20 to the point where more or less of the delivery of pump 16 will be bypassed through relief valve 22.

It will be noted that the yoke 86 may be controlled either by the handle 66 or by the handle 66'. Thus, whichever of the several cams 72 be operated to rotate the shaft 76, the other of the levers 74-74' will be rotated away from their corresponding cam. Thus, each of the manual control levers controls its corresponding valve exclusively and, at the same time, may also control the displacement of pump 18. The pressure responsive displacement regulator 90 acts in the usual manner in case of overload to reduce the pump displacement whenever a predetermined pressure is exceeded.

The conduits 20, 28 and 36 and shaft 76 may extend to include as many duplicate valves as

may be desired, the single pair being shown by way of illustration. Thus, the single prime mover and pressure supply may serve a large group of hoist winches and provide selective operation of any one of them in either direction and also selective operation of any two of them in opposite directions.

While the form of embodiment of the invention as herein disclosed constitutes a preferred form, it is to be understood that other forms might be adopted, all coming within the scope of the claims which follow.

What is claimed is as follows:

1. In a fluid power transmission system the combination with a variable displacement pump and a fixed displacement pump, of a plurality of fluid motors for operation selectively by fluid delivered by said first pump for one direction of operation and by the other pump for the other direction of operation, individual control valves for selectively connecting said motors individually with either pump for the corresponding direction of operation, said valves being connected with each pump in a parallel circuit, and means for operating said valves individually and simultaneously controlling the displacement of the first pump.

2. In a fluid power transmission system the combination with a unidirectional delivery, variable displacement pump, of a plurality of fluid motors for operation selectively by fluid delivered by said pump, individual control valves for selectively blocking or opening communication between the pump and each motor, said valves being connected with the pump in parallel, individual operators for each valve, means for varying the pump displacement, a common connection between each of said operators and said means whereby the pump displacement may be increased by operation of any operator in a direction tending to open its respective valve, and additional pressure responsive means for reducing pump displacement upon the attainment of a predetermined pressure independently of the position of said operator.

3. In a fluid power transmission system the combination with a unidirectional delivery, variable displacement pump, of a plurality of fluid motors for operation selectively by fluid delivered by said pump, individual control valves for selectively blocking or opening communication between the pump and each motor, said valves being connected with the pump in parallel, individual operators for each valve, means for varying the pump displacement, a common connection between each of said operators and said means whereby the pump displacement may be increased by operation of any operator in a direction tending to open its respective valve, said connection including a member extending adjacent each operator and a lost motion mechanism intermediate each operator and said member, and additional pressure responsive means for reducing pump displacement upon the attainment of a predetermined pressure independently of the position of said operator.

WARREN P. WILLETT.
